US00D783961S

(12) United States Design Patent (10) Patent No.: US D783,961 S
(45) Date of Patent: * Apr. 18, 2017

(54) FOOTWEAR OUTSOLE

(71) Applicant: Rocky Brands Inc., Nelsonville, OH (US)

(72) Inventor: Steven Jamieson Nelson, Lancaster, OH (US)

(73) Assignee: Rocky Brands, Inc., Nelsonville, OH (US)

() Term: 15 Years

(21) Appl. No.: 29/547,805

(22) Filed: Dec. 8, 2015

(51) LOC (10) Cl. 02-04

(52) U.S. Cl.

USPC D2/951; D2/947

(58) Field of Classification Search

USPC ..... D2/947, 902, 906, 908, 916, 925, 946, D2/948–962, 977; 36/1, 1.5, 3 B, 22 R, 36/24.5, 25 R, 28, 32 R, 34 R, 59 C, 36/67 A, 101–107, 114–116, 117.3, 117.4, 36/124–136; D12/544

(57) CLAIM

The ornamental design for a footwear outsole, as shown and described.

DESCRIPTION

FIG. 1 is a perspective view of a footwear outsole according to my new design;

FIG. 2 is a front view thereof;

FIG. 3 is a rear view thereof;

FIG. 4 is a left side view thereof;

FIG. 5 is a right side view thereof;

FIG. 6 is a top side view thereof; and,

FIG. 7 is a bottom side view thereof.

The broken lines showing a footwear upper in the figures indicate environment and form no part of the claimed design. The remaining broken lines in the figures showing stitching on the footwear outsole form a part of the claimed design.

1 Claim, 5 Drawing Sheets
